UNITED STATES PATENT OFFICE.

SIDNEY A. KELLER, OF NEW YORK, N. Y.

DESIGN FOR A CORNER FOR BLOTTING-PADS OR SIMILAR ARTICLES.

SPECIFICATION forming part of Design No. 36,027, dated August 26, 1902.

Application filed July 23, 1902. Serial No. 116,747. Term of patent 3½ years.

To all whom it may concern:

Be it known that I, SIDNEY A. KELLER, a citizen of the United States, and a resident of New York, borough of Manhattan, in the county of New York and State of New York, have invented and produced a certain new, original, and ornamental Design for a Corner for Blotting-Pads or Similar Articles, of which the following is a specification.

10 In the accompanying drawing I have illustrated a corner for blotting-pads or similar articles ornamented in accordance with my invention.

15 The leading or characteristic features of my design are the outline or contour, the butterfly-head, consisting of the head of a female figure having wings extending therefrom, and the floral decoration, consisting of leaves and flowers partially surrounding a plain shield.

Referring to the drawing, A represents the 20 head of a female figure having the wings B extending therefrom and below which is the plain shield C, the latter being surrounded by the floral decoration D D, all being in relief.

What I claim is—

25 The ornamental design for a corner for blotting-pads, or similar articles, substantially as herein shown and described.

Signed at New York, borough of Manhattan, in the county of New York and State of 30 New York, this 21st day of July, A. D. 1902.

SIDNEY A. KELLER.
